STANDPIPE TURNING DEVICE

Leo I. Kennedy, Lemoyne, Pa.

Application March 2, 1946, Serial No. 651,572

3 Claims. (Cl. 137—21)

1

This invention relates to a stand pipe turning device, and more particularly to a device for turning stand pipes of the type employed in supplying water to locomotive tenders and the like.

The primary object of the invention is to reduce the physical effort required to be exerted in the act of turning a stand pipe into or out of tender-filling position.

Another object is to reduce to a minimum the hazards involved in the turning of stand pipes.

The above and other objects may be attained by employing this invention which embodies, among its features, a ring gear adapted to be carried by the hood commonly affixed to a water column to form a water shed at its junction with the usual stand, and means on the stand cooperating with the ring gear for rotating the water column about the axis of the stand.

Other features include means carried by the stand for engaging the ring gear and supporting it substantially diametrically opposite the ring gear rotating means.

Referring to the drawings:

Figure 1 is an end view of a stand pipe showing the same turned into a position to deliver water to the tender of a locomotive.

Figure 2 is a horizontal sectional view taken substantially along the line 2—2 of Figure 1.

Figure 3 is an end view of Figure 2.

Figure 4 is a transverse sectional view taken substantially along the line 4—4 of Figure 2.

Figure 5 is an enlarged plan view of my improved stand attachment.

Figure 6 is a side view in elevation thereof, portions being shown in section to more clearly illustrate the details of construction.

Figure 7 is an enlarged fragmentary sectional view taken substantially along the line 7—7 of Figure 6, and

Figure 8 is a detail view of the ring gear.

Referring to the drawings in detail, a stand pipe designated generally 10 comprises the usual stand 11 which is bolted or otherwise secured to a platform adjacent a railway track designated generally 12. A water column 13 extends axially through the stand 11 and rises vertically therefrom, to terminate in an elbow 14 which discharges water flowing upwardly through the water column 13 into a discharge funnel 15, the end of which is downturned to direct the contents thereof into the tender 16 of a locomotive 17 standing on the track 12 beside the stand pipe. Carried by the water column 13 near its point of emergence from the stand 11 is a hood 18 which is more or less dome shaped and its lower edge

2

encircles the upper end of the stand in spaced relation thereto. Projecting outwardly from the dome shaped hood 18 are suitable ears 19 between which is pivotally supported, as at 20, a latch 21 which is adapted to cooperate with a notch formed in an upstanding flange 22 carried at the upper end of the stand 11 to serve as a lock holding the water column 13 against rotation relative to the stand.

10 The structure so far recited is such as will be found to be conventional equipment in the railroad industry and forms no part of my invention.

In order to carry my invention into practice, I provide a separable ring gear designated generally 23 which comprises two semi-circular halves 24 carrying, at their inner edges, upstanding flanges 25 which are pierced, as at 26, at spaced points to receive attaching bolts 27, by means of which the ring gear is rigidly fixed to the hood 18 adjacent its lower edge. The under side of each ring half 24 is provided with gear teeth 28 so cut and arranged that when the parts are assembled the teeth 28 cooperate to form a continuous ring gear. Attaching flanges 29 extend outwardly from opposite ends of each ring half 24 and are joined together by attaching bolts 30 in order to complete the ring.

Attached to the stand 11 immediately beneath the lower edge of the hood 18 and diametrically opposed with relation to one another are brackets 31 having aligning openings 32 therein for a purpose to be more fully hereinafter described. Secured to the stand 11 immediately below each bracket 31 is an angularly extending bracket 33, each of which carries, adjacent its upper end, a bearing 34, the opening 35 of which aligns axially with the opening 32 of its respective adjacent bracket 31. Mounted for rotation in the openings 32 and 35 of one pair of brackets 31 and 33 is a drive shaft 36 carrying, near its inner end, a drive pinion 37 which is adapted to mesh with the ring gear 23 so that when the shaft 36 is rotated, the ring gear likewise will be rotated. A hand wheel 38 is fixed to the outer end of the shaft 36 so that the shaft may be rotated at the convenience or desire of the operator of the device.

Mounted for rotation in the brackets 31 and 33, diametrically opposite those carrying the drive shaft 36, is an idler shaft 39 carrying an idler pinion 40 which has meshing engagement with the gear 23 diametrically opposite the pinion 37. It will thus be seen that any tendency of the ring gear 23 to be elevated by reason of the rotation of the pinion 37 will be counteracted by the support-

ing effect of the pinion 40, and consequently the ring gear 23 will be held at all times in proper position about the axis of the stand pipe.

In operation, it will be understood that with the parts assembled as previously described it is only necessary when it is desired to turn the stand pipe into or out of operative position to rotate the hand wheel 38. Assuming that the stand pipe is in inoperative position and it is desired to turn it to discharge the liquid into the tender of a locomotive, it is only necessary to operate the handle of the latch 21 so as to disengage the latch from its recess in the flange 22 and then to rotate the hand wheel 38, thus driving the drive pinion 37 and the ring gear 23 so as to cause the water column 13 to rotate about the longitudinal axis of the stand 11. Due to the relatively large leverage of the mechanical system employed, it is obvious that the amount of manual effort required for turning the stand pipe will be relatively small and also, inasmuch as the operator may stand in one position, the hazards attending the turning of stand pipes will be greatly reduced. Obviously, upon turning the water column 13 to its original position with relation to the stand 11, the latch 21 will again enter the recess in the flange 22 and lock the parts against rotation until manually released for a repeat operation.

While in the foregoing there has been shown and described the preferred embodiment of this invention, it is to be understood that minor changes in the details of construction and combination and arrangement of parts may be resorted to without departing from the spirit and scope of the invention as claimed.

What I claim is:

1. A turning device for a stand pipe of the type which includes a stand, a water column mounted to rotate about the longitudinal axis of the stand, and a hood carried by the water column and enclosing the upper edge of the stand to form a water shed, comprising a ring gear carried by the hood, a pair of spaced brackets fixed to the stand near the ring gear, a drive shaft supported by said brackets to rotate below said ring gear about an axis perpendicular to the axis of the stand, a drive pinion carried by the drive shaft and having meshing engagement with the ring gear, a hand wheel carried by the drive shaft to impart rotary motion to the pinion and thereby turn the ring gear and the water column about the longitudinal axis of the stand, a pair of

spaced brackets secured to the stand diametrically opposite the first-mentioned spaced brackets, an idler shaft mounted in said last-named spaced brackets in axial alignment with the drive shaft and a supporting pinion carried by the idler shaft and meshing with the ring gear diametrically opposite the drive pinion.

2. In an apparatus for watering a locomotive tender, a hollow support stand, a water column extending upwardly through the stand for rotation about its vertical axis therein, an annular hood secured to the column above the stand and enclosing the upper edge of the stand to form a water shed therefor and also for supporting the column, the hood terminating at its lower edge in a ring gear, a plurality of pinions circumferentially spaced and journaled on the stand below the hood to rotate about axes perpendicular to the column and in meshing engagement with the ring gear and supporting the column upon the stand, and a hand wheel carried by the stand operatively connected to one of the pinions for rotating the column.

3. In an apparatus for watering a locomotive tender, a hollow support stand, a water column extending upwardly through the stand for rotation about its vertical axis therein, an annular hood secured to the column above the stand and enclosing the upper edge of the stand to form a water shed therefor and also for supporting the column, the hood terminating at its lower edge in a ring gear, a plurality of pinions circumferentially spaced and journaled on the stand below the hood to rotate about axes perpendicular to the column and in meshing engagement with the ring gear and supporting the column upon the stand, said stand including an annular flange slidably embracing the column to retain the column against lateral movement and the ring gear in coacting relation.

LEO I. KENNEDY.
